UNITED STATES PATENT OFFICE.

JAMES WATSON, OF LONDON, ENGLAND.

BALING-PRESS.

SPECIFICATION forming part of Letters Patent No. 283,838, dated August 28, 1883.

Application filed June 30, 1883. (No model.) Patented in England April 28, 1883, No. 2,155.

To all whom it may concern:

Be it known that I, JAMES WATSON, of London, England, have invented certain new and useful Improvements in Baling-Presses, of 5 which the following is a specification.

My invention consists of improvements in baling-presses, and has special reference to presses in which the cotton, jute, or other material to be formed into a bale receives first a 10 preliminary pressure by one or more rams, and then a final or finishing pressure by one or more other rams.

The primary object of the invention is to obtain an increase in the outturn from the 15 press. For this purpose I construct the press with two sets of boxes, each set being mounted upon a separate column, around which it can be revolved, which columns may be two of the 20 columns or supports of the press. One set consists of two, three, or more deep boxes, each capable of holding sufficient of the bulky or 25 loose material to form a bale. The other set consists of two, three, or more shallow boxes, the depth of each of which is sufficient to hold 30 the material after the preliminary pressure. The respective circles described by the two sets of boxes in their revolution are such that at a given point of the revolution one of the 35 shallow boxes comes exactly over one of the deep boxes. The shallow or upper boxes are each constructed with two main doors, forming the two sides of the box and hinged to one of the ends, with an easing-door forming the other end, and with a top forming a lashing-plate, 40 and in each of the main doors is a toothed sliding stop for supporting the bottom of the bale when the preliminary pressure has been completed; or there may be a sliding stop in one door only, which stop will move right 45 across under the bale and enter spaces in the other door. The main doors are also constructed near their upper part with grooves, mortises, or recesses corresponding with fillets, tenons, or projections on the top lashing-plate, 50 and they also have vertical grooves to receive the edges of the easing-door, so that when these doors are closed they firmly hold this lashing-plate and the easing-door.

Figure 1 of the annexed drawings is a front 55 elevation, and Fig. 2 a side elevation, of a press constructed according to my invention,

as hereinbefore described. Fig. 3 is a section through 1 1 of Fig. 1, with the lashing-plates broken off. Fig. 4 is a section through 2 2, 55 Fig. 1.

A', A^2, A^3, A^4 are a set of deep boxes, each capable of holding sufficient of the bulky and loose material to form a bale. This set of boxes is mounted on a column, B, around which it can be revolved. These I will call, for brevity, 60 the "preparatory boxes." Upon another column, C, is mounted a set of shallow boxes, which I will call "finishing-boxes." (There are two of these boxes in the arrangement shown.) Each of these shallow boxes is composed of two main doors, D, D', D'', D''' , forming the two sides of the box and hinged to the inner end, E, E' , an easing-door, F, F' , forming the other end, and a top, G, G' , forming a lashing-plate. The center piece, E, E' , which constitutes the inner 65 end of each of these boxes, is mounted on the column C, around which it can be revolved together with the main doors and other parts which go to make up the boxes. The columns B and C form two of the columns or supports 70 of the press. The two lashing-plates G, G' may either be formed in one piece, which is rigidly fixed to the center piece, E, E' , and embraces the column C, or they may be made in 75 separate pieces, which are likewise rigidly 80 fixed to the piece E. It will be seen that the respective circles described by the two sets of boxes are such that at a given point of their 85 respective revolutions one of the shallow boxes comes exactly over one of the deep boxes.

In each of the main doors D, D', D'', D''' is a toothed sliding stop, H, for supporting the bottom of the bale in the shallow box. They may be made to slide in and out, as required, by any suitable arrangement. That shown 90 in the drawings consists of a shaft, I, worked by a handle, J, (or otherwise,) and carrying pinions K to gear into racks L on the sliding stops. The sliding stops are shown in position below the bale in Fig. 4, and also in 95 the closed doors D, D' , Fig. 3, while they are shown fully withdrawn in the open doors D', D'' , Fig. 3. The doors D, D', D'', D''' are constructed with grooves M, M near their upper part, corresponding with fillets or projections 100 N, N on the lashing-plates G, G' , and also with vertical grooves O, O, to receive the edges of

the easing-doors F F', so that when the doors D D D' D' are closed they firmly hold their respective lashing-plates and easing-doors.

5 P P are screws worked by hand-wheels Q Q, for assisting in the adjustment of the boxes and for pressing home and relieving the easing-doors, as required.

R is the ram for effecting the preliminary pressure, and S its follower.

10 T T are the rams for effecting the finishing or final pressure, and U is their follower.

V is the ground-floor, and W the filling-floor. The latter may be level with the top of the preparatory boxes A' A² A³ A⁴, or lower, 15 as thought best. The part X of the floor W is shown as made to revolve with these boxes.

Z, Fig. 2, is a hasp or hinged plate carried by one of the main doors of each box, to pass behind the easing-door and through an opening, Y, in the other main door, where it is secured by a pin or otherwise.

The action of the press is as follows: One 20 of the preparatory boxes (A', for example) having been filled with cotton, (or other material to be formed into a bale,) and one of the shallow or finishing boxes being in position, as seen in the figures, exactly over this preparatory box, the ram R (or rams) for effecting the preliminary pressure is caused to rise 25 through the deep box, so as to force the cotton entirely into the upper box. The sliding stops H H in the main doors D D are then pushed in, so as to enter between grooves in the follower S, and thus relieve the follower from 30 the bale. The follower S can thus be allowed to descend as soon as the preliminary ram R is released from the pressure which raised it. As the follower S descends the set of upper or 35 finishing boxes is moved round so as to bring the box containing the bale exactly over the rams T, for giving the final or finishing pressure, (the screw P being screwed in to insure proper adjustment of the box and to hold the easing-door after the side doors are subsequently opened,) while by the same movement 40 an empty upper box has taken its place above the preliminary ram R, another preparatory box, A⁴, already filled with cotton, being swung round as soon as the ram R falls 45 clear of them. The finishing-rams T T are meanwhile caused to rise until the teeth of the follower U enter between the teeth of the sliding stops H H and relieve them from the bale. These sliding stops are then moved out 50 and the main doors D D are opened, the finishing-rams T are caused to rise farther to give the final pressure, the bale is hooped or roped, and then the end easing-door, F, is relieved. The finishing-rams T are now lowered, 55 the bale is tumbled out of the press, and the main doors D D are again closed and locked, ready to be turned into position for another charge.

It will be readily understood that by the 60 arrangement above described, while one bale is receiving its final pressure another bale

may be receiving its preliminary pressure; or, if the whole pump-power is common to both pressures, the preliminary ram will be raised and the stops be pushed in after a bale has 70 been pressed by the finishing-ram—that is to say, during the time occupied in pulling tight and fastening the ropes or hoops, lowering the finishing-ram, tumbling out the bale, and closing and locking the main doors, and during this time also one or more of the preparatory boxes are being filled with cotton or jute, ready for the preliminary pressure. The outturn of the press is consequently very great.

75 In order to facilitate the work, I cause the set of preparatory boxes to turn automatically by means of a weight and gearing. The weight is raised by the preliminary ram during its ascent, and is left near the top of the stroke after the ram is descended. When the boxes 80 are freed from the device which holds them during the ascent of the ram, the weight is able to exert its power and descends gradually, and in so doing causes the boxes to 85 revolve by means of the gearing.

90 The arrangement for automatically revolving the preparatory boxes is seen in Fig. 1. A rod, a, is fixed to the follower S, and passes freely through the large weight or weights b. On its lower end is a nut, c. d d are two chains, which also pass through the weight b, and are secured to its under side by nuts e e. These chains are carried over a barrel or drum, f, which is loose on the shaft g. They pass once or oftener around this barrel, which is suitably grooved to receive them, and their ends eventually fall on the side of the barrel opposite to that on which the chains are directly attached to the weight b. A much smaller weight, h, is attached to the ends of the chains. i is a collar keyed on the shaft g, and j j are spring-pawls carried by this collar and taking into teeth in the barrel f. The barrel is free to revolve on its shaft g in the direction in which the small weight h pulls it, but is prevented by the pawls from being revolved in the opposite direction on the shaft by the large weight b, so that this shaft, when not held, is caused to rotate, together with the collar i and pawls, by the large weight b, the effect of 105 which is that rotation on the column B is given to the boxes A' A² A³ A⁴ by the intermedia- 110 tion of the bevel-wheels k k, rod l, and gearing m.

115 To make the action clearly understood, I 120 will suppose the follower S to be at the bottom of its stroke, as seen in dotted lines in Fig. 1. The lower end of the rod a will be at the bottom of the well n, and the weight b, I will suppose also there, and the small weight h will therefore be at the top of the well, near the barrel f. As the ram R and follower S rise, the rod a also rises, and by means of the nut c lifts the weight b with it. The weight h at the same time descends, causing the barrel f to rotate 130 and taking up the slack of the chains d d. As the ram R descends—that is to say, after the

bale is held by the sliding stops H H—the boxes A' A² A³ A⁴ are prevented turning by any suitable holding device, so that the rod a passes down through the weight b, leaving this 5 weight free to fall as far as the nut c as soon as the holding device is released. When this release is effected, the weight b falls gradually, and thereby, through the gearing already described, causes the four boxes to turn around 10 the column B until the next box, A⁴, is brought into position over the ram R. A similar arrangement is applied to the set of upper finishing-boxes. This is also seen in Fig. 1, b' being the large weight; h', the small weight; a', 15 the rod passing through the large weight, and connected to the follower S; f', the barrel, and k' k' the bevel-gearing. The same arrangement can be applied to other baling-presses in which a set of boxes has to be swung round.

20 What I claim, and desire to secure by Letters Patent, is—

1. The combination, in a press, of a preparatory ram and a finishing-ram, said rams arranged in parallel planes, a set of finishing-boxes mounted to revolve around an axis over said rams, and arranged to be brought successively into coincidence therewith, and a set of preparatory boxes, also mounted to revolve around an axis below the finishing-boxes, and 25 arranged to be brought into coincidence, successively, with the preparatory ram and a finishing-box, whereby the preparatory ram is enabled to force the material from the preparatory box into the finishing-box, and where- 30 by the latter box, with the partly-finished bale, may be swung around to the finishing-ram, substantially as set forth.

2. The revolving set of boxes A' A² A³ A⁴, in combination with the revolving set of boxes 35 formed of the main doors D D' D' D', inner ends, E E', easing-doors F F', and top lashing-plates, G G', substantially as herein set forth and shown.

3. The combination, to form the finishing-box, of the fixed inner end E, the sides D D', 45 hinged thereto in the form of doors, the easing-door F, the hinged top G, the toothed sliding stop H, and means, substantially as described, for operating said stop, all arranged substantially as set forth.

4. The combination, with the lashing-plate, of the hinged sides D, provided with grooves M, to receive the edges of said plate, substantially as set forth.

5. The combination, with the preparatory 55 ram and the preparatory boxes mounted to revolve around an axis and to be brought successively over the said ram, of the mechanism, substantially as described, for automatically revolving said boxes, substantially as set forth. 60

6. In combination with the set of boxes A' A² A³ A⁴, the rod a, weight b, nut c, chains d d, barrel f, shaft g, weight h, collar i, pawls j j, wheels k k, rod l, and gearing m, substantially as and for the purpose set forth and 65 shown.

7. The combination, with the finishing-boxes mounted to revolve around an axis, whereby they are brought successively over the rams, 70 of the rams S and T, and mechanism, substantially as described, for revolving the said finishing-boxes, as set forth.

8. The combination, with the finishing-boxes mounted to revolve around an axis, as shown, of the weights b' and h', rod a', barrel f', and 75 gearing k, all arranged to operate substantially as set forth.

In witness whereof I have hereunto signed my name in the presence of two subscribing witnesses.

JAMES WATSON.
